UNITED STATES PATENT OFFICE.

GUY B. PETTER, OF SOMERSET, ENGLAND, ASSIGNOR TO PETTERS, LIMITED, OF SOMERSET, ENGLAND.

APPARATUS FOR ELECTRIC HEATING OF ENGINES OF THE HOT-BULB TYPE BEFORE STARTING.

Application filed January 4, 1921. Serial No. 434,904.

To all whom it may concern:

Be it known that I, GUY BAZELEY PETTER, of Nautilus Works, Yeovil, Somerset, England, a subject of the King of Great Britain and Ireland, have invented certain new and useful Improvements in Apparatus for Electric Heating of Engines of the Hot-Bulb Type before Starting, of which the following is a specification.

10 This invention relates to electric heating and ignition apparatus for internal combustion engines of the hot bulb type before starting, in which apparatus a coil of wire or other suitable heating element is heated 15 by an electric current and the said heating coil is used to ignite the mixture of fuel and air in the combustion chamber of the engine.

An arrangement has heretofore been proposed in which the heating element is contained in a plug adapted to be screwed or otherwise fixed into the combustion chamber in such a manner that the fuel spray issuing from the fuel injection nozzle comes 25 in contact with the said heating element, thereby effecting ignition.

The object of my invention is to provide an improved arrangement by means of which the heating element can be withdrawn from the inside of the combustion chamber after ignition has been effected and the heat of combustion has raised the temperature of the walls of the chamber sufficiently to permit of ignition being there- 35 after continued by means of surface ignition.

In carrying out my invention in the preferred form I fix the heating element in the neck of a mushroom or poppet valve, 40 fitted into the combustion chamber near the fuel injection nozzle in such a manner that when the valve is closed upon its seat, the heating element is withdrawn outside the chamber, but when the valve is opened by 45 an amount of 1" more or less, the head of the valve passes across the line of action of the fuel spray and brings the heating element into position so that some of the spray comes in contact with it, thereby causing ignition.

In order that this invention may be clearly understood and readily carried into practice, constructions embodying the same will now be described by way of illustra-

tion with the aid of the accompanying 55 drawings in which Fig. 1 is a part sectional elevation, shewing the improved arrangement of the ignition apparatus, and a device for placing the valve carrying the heating element in and out of operative position; Fig. 2 is a similar view showing a modification of the device for placing the said valve in and out of operative position and also means for withdrawing the valve for inspection.

Referring to the drawings, the combustion chamber is supplied with fuel from a sprayer 2 adapted to deliver a jet or spray of fuel oil fed from the fuel pump (not shewn).

The electrically heated wire element 4 is carried upon the mushroom valve 3 which in the drawing is shown in its forward position in which the heating element 4 projects into the combustion chamber so that 70 part of the fuel spray falls upon the said element.

The heating element 4 is attached at one end to the valve head 5 which forms an earth connection, and at the other end it 75 is attached to a wire 6 passing through the hollow valve stem and insulated by means of insulating washers 7 and 8.

The wire 6 is provided at its outer end with suitable cable connections to receive 80 the cable 9 for supplying current for heating the wire element from a dynamo or storage battery.

By means of a sleeve 10 the valve stem and connected parts are passed through the 90 water cooled section of the walls surrounding the combustion chamber.

In the arrangement shown in Fig. 1 a lever 11 controls and operates the forward and backward movement of the valve the 95 lever being secured in one position or the other by means of a quadrant 12 fitted with stops or pegs 13 and 14 for engaging the lever and thus locating the valve in the forward or backward position. The valve stem 100 is preferably provided with a second valve head arranged outside the engine as shown at 17 for closing the combustion chamber and preventing the escaping of gas when the valve is in the forward position.

Means must be provided for preventing the rotation of the valve stem in order that the heating element 4 may always be turned

towards the spray. In the arrangement shown in Fig. 1 of the drawings this is done by providing the lever 11 with a forked end 15 the forks of which fit into 5 flat recesses 16 on opposite sides of the valve stem, thereby preventing rotation.

In the arrangement shown in Fig. 2 the movement of the valve is controlled by the hand wheel 18 which works on the square 10 screw thread 19 provided on the valve stem 3. A loose bush 20 is fitted inside the sleeve 10, being held in position by the valve casing 21 and prevented from rotating by the pin 22. The said pin passes through a hole 15 in the bush 20 into a groove 23 cut in the valve stem 3 for the purpose of preventing the said valve from turning. A split collar 24 supported on the valve casing 21 fits loosely in a circular groove cut in the hand- 20 wheel 18 with just sufficient clearance to allow for contraction of the valve stem 3, so that by turning the hand-wheel, the valve moves either in or out.

It will be understood that the object of 25 the loose bush is to provide means whereby the valve 3 may easily be removed for examination or attention by removing the nuts 25 and 26 holding the valve casing 21, the bush 20 being then withdrawn with the 30 valve.

Other modifications of the arrangements shown in the drawings may be adopted without affecting the principle of our invention, and it is pointed out that while we 35 have specified a mushroom or poppet valve in the preferred arrangement described above, any suitable member may be substituted which is capable of a to and fro movement and is adapted to shut off the heat of 40 the combustion chamber from the element in the inactive position of the latter.

What I desire to claim and secure by Letters Patent is:—

1. In an internal combustion engine, ignition apparatus comprising in combination 45 a fuel injection device, a recess in the wall of the combustion chamber near the said device, a valve controlling the communication between the recess and the interior of 50 the combustion chamber, a stem carrying the valve, an electric heating element mounted in the stem with its exposed surface towards the fuel injection device, means for preventing rotation of the stem, connections to 55 the heating element from a source of current, and means for opening and closing the valve and simultaneously moving the heating element into and withdrawing it from the combustion chamber.

60 2. In an internal combustion engine, ignition apparatus comprising in combination a fuel injection device, a passage through the wall of the combustion chamber in the vicinity of the said device, a hollow stem ar- 65 ranged to slide in the said passage, a valve

head on the part of the stem outside the engine adapted to close the outer end of the passage in the inner position of the stem, another valve head on the inner end of the stem adapted to close the inner end of the 70 passage in the outer position of the stem, an opening in the wall of the hollow stem at the inner end of the latter on the side nearest the injection device, an electric heating element arranged within the stem opposite 75 the said opening, connections within the stem from a source of current to the heating element, means for preventing the stem from rotating, and means for moving the stem to its inner or outer position at will. 80

3. In an internal combustion engine, ignition apparatus comprising in combination a fuel injection device, a passage through the wall of the combustion chamber in the vicinity of the said device, a valve controlling 85 the communication between the passage and the interior of the combustion chamber, a valve stem, an electric heating element carried upon the stem, connections thereto from a source of current, a casing secured to 90 the outside of the combustion chamber concentric with the said passage and enclosing a part of the valve stem, an external screw-thread on the said part of the valve stem, a hand-wheel revolubly secured upon the 95 casing, a hole through the hub of the hand-wheel, an internal screw thread in the wall of the said hole engaging with the external screw thread on the valve stem, and means for preventing the rotation of the valve 100 stem.

4. In an internal combustion engine, ignition apparatus comprising in combination a fuel injection device, a passage through the wall of the combustion chamber in the vicinity of the said device, a valve controlling 105 the communication between the passage and the interior of the combustion chamber, a valve stem, an electric heating element carried upon the stem, connections thereto from a source of current, a casing secured to 110 the outside of the combustion chamber concentric with the said passage, an external square screw thread on the said part of the valve stem, a hand-wheel revolubly secured upon the casing, a hole through the hub of the hand-wheel, an internal square screw thread in the wall of the said hole engaging 115 with the external square screw thread on the valve stem, and means for preventing the 120 rotation of the valve stem.

5. In an internal combustion engine, ignition apparatus comprising in combination a fuel injection device, a passage through the wall of the combustion chamber in the vicinity of the said device, a loose bush within 125 the said passage for facilitating withdrawal of the apparatus for inspection or repair, a hollow valve stem enclosed within the bush, a longitudinal groove in the exte- 130

- rior of the said stem, a pin passing through the loose bush and projecting into the said groove in the valve stem, a valve on the stem controlling the communication between the 5 passage and the interior of the combustion chamber, an electric heating element carried by the hollow valve stem, connections thereto passing through the said hollow stem from a source of current, a casing secured 10 to the outside of the combustion chamber concentric with the said passage and enclos-
- ing a part of the valve stem, an external screw thread on the said part of the valve stem, a hand-wheel revolubly secured upon the casing, a hole through the hub of the 15 hand-wheel, and an internal screw thread in the wall of the said hole engaging with the external screw thread on the valve stem.
- In testimony whereof I have signed my name to this specification.

GUY B. PETTER.
